BUILDING

Lawrence W. Weaver, Fullerton, Calif., assignor of thirty-three and one-third percent each to Lavelle D. Barber, Anaheim, and George C. Faith, Costa Mesa, Calif.

Filed Nov. 26, 1969, Ser. No. 20,281

Term of patent 14 years

Int. Cl. D25—04

U.S. Cl. D13—1

The sole figure is a front elevation view of the present building.

The building is circular and the back surface not shown is the same in appearance as the front and side surfaces shown except that there is no entrance door in the back surface.

I claim:

The ornamental design for a building, as shown and described.
